UNITED STATES PATENT OFFICE

HAROLD ARMOUR PARSON, OF FAWN LAKE, ALBERTA, CANADA

RAILWAY CROSSING SIGNAL AND GUARD

Application filed December 2, 1931. Serial No. 578,577.

The invention relates to a railway crossing signal and guard and more especially to an automatically operated device for warning vehicles of the automobile type of an approaching train at a crossing.

The primary object of the invention is the provision of a device of this character wherein in an approaching train at a crossing will automatically operate the same so as to signal the approach of said train and in event that an operator of a vehicle such as an automobile fails to heed the signal and drives upon the track the tires of such vehicle will become punctured to penalize the intruder or the operator of the automobile in disobedience of the signal.

Another object of the invention is the provision of a device of this character wherein the moving train when approaching the crossing will automatically operate the same both for the setting of the signal and the puncturing medium and also when leaving the crossing to return the signal and the puncturing medium to ineffective positions, the device being operable by a train when approaching the crossing in either direction.

A further object of the invention is the provision of a device of this character which is comparatively simple in construction, automatically operated, thoroughly reliable and efficient in its purpose, strong, durable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:—

Figure 1 is a fragmentary top plan view of a railway track showing the device constructed in accordance with the invention applied thereto and in normally inactive position.

Figure 2 is a side elevation, the same being partly in section and showing the cow catcher of a locomotive with the trip means for the device.

Figure 3 is a view similar to Figure 2 looking from the opposite side of the track.

Figure 4 is a sectional view on the line 4—4 of Figure 1 looking in the direction of the arrow.

Figure 5 is a sectional view on the line 5—5 of Figure 4, the same being on an enlarged scale.

Figure 6 is a fragmentary vertical longitudinal sectional view through one of the yieldable or compensating connections arranged in the device.

Figure 7 is an enlarged fragmentary side elevation showing the puncturing medium set at the crossing.

Figure 8 is a fragmentary enlarged sectional view on the line 8—8 of Figure 1 looking in the direction of the arrow.

Figure 9 is a sectional view on the line 9—9 of Figure 1 looking in the direction of the arrow.

Similar reference characters indicate corresponding parts throughout the several views in the drawings.

Referring to the drawings in detail, A designates a portion of the rails of a single track and B the cross ties; these portions of the rails A of the track for the purpose of illustration are at a road crossing intersecting said track and arranged at this location on one rail at the outer side thereof is a vertically movable horizontally disposed tire puncturing medium including a plate 10 having bolted or otherwise made fast thereto a plurality of puncturing spurs or teeth 11, these being spaced apart and protrude above the upper edge of said plate. The plate 10 is provided with spaced longitudinal slots 12, these being arranged near opposite ends and in which engage the upper pivotal connections 13 of rock-

ing arms 14, the latter being journaled at their lower ends as at 15 in bearings 16 located at the base of said rails so that on the swinging of the arms 14 in one direction the plate will become lowered and when moved in the opposite direction said plate will be raised to protrude the spurs or teeth 11 above the plane of the treads of the rails A, so that when a motor vehicle crosses the track the spurs or teeth 11 will penetrate the tires and thus

puncture the same. The plate 10 is fitted between vertical guides 17 so that it will move vertically therebetween to lowered or raised position and when in lowered position the spurs or teeth 11 will be below the treads of the rails A and inactive for tire puncturing purposes. The pivotal connections 13 are adapted for free movement in the slots 12 and are connected with the throw rod 18, the latter being projected beyond the plate 10 at opposite ends thereof and these projected ends are pivoted at 19 with rocking arms 20 corresponding to the arms 14, the arms 20 being also pivoted at their upper ends through the medium of links 21 with rocking levers 22, the latter being supported for rocking movement by bearing studs 23, these being suitably mounted in the web of the rail A spaced beyond opposite ends of the plate 10 the required distance. These levers 22 are operated by the depressible trips 24 and 25 respectively so that on approach of a train upon the track in either direction relative to the crossing either lever 24 or 25 will be operated to move the plate 10 into lowered position after the automatic setting thereof to raised position in a manner presently described.

Located the required distance away from the crossing intersecting the track and arranged on the rail A carrying the parts hereinbefore described are actuating levers 26, these at their lower ends being connected by pivots 27 with shift rods 28, the latter being connected with the levers 22 and each has included therein a turnbuckle 29 and a spring tensioned compensating connection 30, the latter being employed to avoid the breaking of the parts when operated should the plate 10 become jammed or adjunct operative parts thereof, while the turnbuckle 29 is employed to take up slack or for adjustment purposes. Each actuating lever 26 carries an upper section 31 connected through the medium of a pivot 32 with said lever and this pivot 32 carries a spring 33 active upon the section 31 to normally hold it in alignment with the lever 26 yet permitting the section 31 to become depressed against the resistance of the spring 33 when actuated in one direction to avoid operating the plate 10, the section 31 being extended above the tread of the rail A and carrying a rubber tired contact roller 34 at its upper end with which is adapted to engage a striker 35 which extends entirely across the cow catcher 36 of a locomotive and this striker 35 is operative upon the lever 26 upon the approach of a train to the crossing to move the plate 10 to raised position where the spurs or teeth 11 will be arranged for puncturing purposes of tires of an automobile when running upon the track in front of the train approaching the crossing. It will be apparent that the actuating lever 26 with the section 31 is provided with a break joint at the pivot 32 so that said lever will be effective for operation in

one direction only and that is to say in the direction of the approaching movement of the train to the crossing, whereas the train moving in the reverse direction will be ineffective for actuating the lever 26 to operate the plate 10.

It will be obvious from Figures 1 and 2 of the drawings that an actuator lever 26 is located on each side of the crossing and a train approaching from either side of the crossing thereto will automatically operate the puncturing medium including the plate 10 and the spurs or teeth 11 by the striker 35 on the cow catcher 36 engaging the wheel 34 causing the lever 26 to rock and thus imparting movement to the plate 11 for the raising thereof to operative position. Likewise the trips 24 and 25 are arranged on opposite sides of the crossing between the same and the levers 26 so that when the train nears the crossing or in immediate proximity thereto the striker 35 will operate upon either of the trips 24 or 25 according to the direction of travel of the train for the automatic lowering of the plate 10 with the spurs or teeth 11 thereon to ineffective position.

On the rail A opposite that having arranged therewith the plate 10 and carried by one of the cross ties B at one side of the crossing is a signal stand 35' in which is arranged a vertically disposed rotatable flag signal staff 36' having at its upper end a panel or flag 37 on which is arranged a signal such as the word "Stop" as at 38 and this panel or flag 37 normally is in non-signalling position. Carried by the staff 36' within the stand 35' is an arm 39, which through the medium of a ball and socket connection 40 with the actuator crank 41, the latter being fixed to a turning shaft 42 suitably journaled in the stand 35' and bearing 43 on the base of the rail next thereto. This shaft 42 at its inner end through the connections 44 in association with the actuator levers 45, these being identical to the levers 26 will be automatically operated for the turning of the panel or flag 37 to signalling position at the crossing. The connections 44 contiguous with the stand 35' are fitted with the trip 46 corresponding to the trip 25 and this trip is operative to return the signal panel or flag 37 to non-signalling position when the train has reached the crossing. The connections 44 include the turnbuckles 47 and compensating connections 48 identical with the turnbuckle 29 and connections 30 so that proper adjustment may be had and also to prevent the breaking of the working parts of the signal mechanism should any part thereof become jammed.

The connections 44 for a major portion thereof are incased in a piping 49 and likewise the plate 10 is incased in a housing 50 to protect these against the weather elements.

In the operation of the device when a train

approaches the road crossing of the track from either direction at opposite sides thereof at a determined distance therefrom the striker 35 will first engage the lever 45 for operating first the signal panel or flag 37 to bring it to signalling position and thereby warn a motorist approaching the crossing of the danger of the oncoming train. At a later interval the striker 35 will operate the actuator lever 26 so that the plate 10 with its spurs or teeth 11 will be raised at the crossing and in event that such motorist fails to heed the signal and drives upon the track the spurs or teeth 11 will puncture the tires of the vehicle to penalize such motorist for not obeying such signal. When the train reaches the road crossing the striker 35 will operate first upon the trip 24 to lower the plate 10 with the spurs or teeth 11 thereon to ineffective position, then almost immediately thereafter will operate the trip 46 which will cause the automatic shifting of the panel or flag 37 to non-signalling position. When the train passes the crossing in the same direction of travel and strikes the trip 25 and actuator levers 26 and 45 respectively at the other side of the crossing these will be lowered, the plate 10 having been previously lowered with the signal panel or flag 37 in non-signalling position.

On the reverse approach of the train the striker 35 will then actuate the said actuator levers 26 and 45 at that side of the crossing approached by the train for operating the device for signalling and penalizing purposes. Then when the train reaches the crossing it will operate first the trip 25 to lower the plate 10 and then operate the trip 46 for the turning of the signal panel or flag 37 to non-signalling position. Thus it will be seen that the plate 10 will be automatically operated by the train and likewise the signal panel or flag 37 irrespective of the direction of the travel of the train upon the track and in this manner a motorist will be warned at a crossing of the oncoming train thereto and on disobedience of such signal will be penalized by the puncturing of the tires of the vehicle driven by the motorist by the spurs or teeth 11 in the plate 10 of the device.

What is claimed is:—

1. The combination with a track at a road crossing, of a plurality of rocking arms arranged longitudinally of the track, a plate carried by said arms and having teeth to protrude above the tread of the track on movement of the arms in one direction, links pivoted to the ends of the plate, levers pivoted to the links, actuator levers, shift rods connecting the first and second named levers and each having a turnbuckle and tension compensating connection, and wheeled spring tensioned members carried by the actuator levers and projected above the tracks.

2. The combination with a track at a road crossing, of a plurality of rocking arms arranged longitudinally of the track, a plate carried by said arms and having teeth to protrude above the tread of the track on movement of the arms in one direction, links pivoted to the ends of the plate, levers pivoted to the links, actuator levers, shift rods connecting the first and second named levers and each having a turnbuckle and tension compensating connection, wheeled spring tensioned members carried by the actuator levers and projected above the tracks, and depressible actuator levers connected with the first named levers and located spaced from said first named actuator levers.

3. The combination with a track at a road crossing, of a plurality of rocking arms arranged longitudinally of the track, a plate carried by said arms and having teeth to protrude above the tread of the track on movement of the arms in one direction, links pivoted to the ends of the plate, levers pivoted to the links, actuator levers, shift rods connecting the first and second named levers and each having a turnbuckle and tension compensating connection, wheeled spring tensioned members carried by the actuator levers and projected above the tracks, depressible actuator levers connected with the first named levers and located spaced from said first named actuator levers, and means on a train to operate said actuator levers on approach to the crossing at either side thereof.

In testimony whereof I affix my signature. 100
HAROLD ARMOUR PARSON.
